UNITED STATES PATENT OFFICE.

CHARLES E. STANLEY, OF CHICAGO, ILLINOIS.

DESIGN FOR A BICYCLE-SADDLE.

SPECIFICATION forming part of Design No. 27,730, dated October 12, 1897.

Application filed March 5, 1896. Serial No. 581,880¹. Term of patent 7 years.

To all whom it may concern:

Be it known that I, CHARLES E. STANLEY, a citizen of the United States, residing at Chicago, county of Cook, and State of Illinois, 5 have invented and produced a new and original Design for Velocipede-Saddles, of which the following is a specification, reference being had to the accompanying drawings, showing had to the accompanying drawings, showing a part thereof, in which—

10 Figure 1 is a plan view of my design for velocipede-saddle. Fig. 2 is a cross-sectional view on the line x x of Fig. 1.

The leading feature of my design consists in a hollowed-out or depressed portion A, 15 which is located at the front of the saddle and which may be said to be positioned at

the front of the seat portion B of the saddle and at the rear of the horn D thereof, the sides of this depressed portion being farther- 20 est apart in proximity to the seat portion and drawing toward each other and decreasing in height as they approach the horn D, which is in a lower plane relative to the general plane of the saddle.

What I claim is—

25 The design for a bicycle-saddle as herein described and set forth.

CHARLES E. STANLEY.

Witnesses:

L. W. BULKLEY,
HARRY WHITE.
